UNITED STATES PATENT OFFICE.

HUBERT F. KRANTZ, OF BROOKLYN, NEW YORK, ASSIGNOR TO KRANTZ MANUFACTURING COMPANY, INC., OF BROOKLYN, NEW YORK, A CORPORATION OF NEW YORK.

SWITCH MECHANISM.

1,342,548.

Specification of Letters Patent. Patented June 8, 1920.

Original application filed August 2, 1917, Serial No. 184,011. Divided and this application filed February 11, 1919. Serial No. 276,346.

To all whom it may concern:

Be it known that I, HUBERT F. KRANTZ, residing at Brooklyn, in the county of Kings and State of New York, have invented certain new and useful Improvements in a Switch Mechanism, of which the following is a specification.

This is a division of pending application Serial No. 184,011, multiple unit safety switch board, filed August 2, 1917, and the invention herein described and claimed relates to a switch mechanism.

The object of the invention is to provide an improved switch mechanism, together with means for governing the operation thereof in accordance with the position of a guard member which is associated therewith, and inversely to govern the position of the guard member in accordance with the position of the switch mechanism.

A further object is to provide a switch mechanism which, while particularly adapted for use in connection with the multiple unit switch board shown and described in said pending application, is nevertheless adapted for use in individual switch boxes and in other connections.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings which are to be taken as a part of this specification, and in which I have shown merely a preferred form of embodiment of the invention:

Figure 1 is a rear elevational view of a switch board constructed in accordance with this invention.

Fig. 2 is a perspective view of the major portion of the switch board of Fig. 1, showing one of the switch units in position to be moved into its respective stall.

Fig. 3 is a rear elevational view of a part of the structure shown in Fig. 1, enlarged to show the details of construction of one of the stalls, together with the arrangement of

parts of the switch unit in position therein, the guard members, or doors, for the stalls being removed and a portion of the switch unit being broken away and shown in section to better disclose its construction.

Fig. 4 is a vertical transverse sectional view taken substantially upon the plane of line IV of Fig. 3, the parts of the switch mechanism being shown in the "on" position and the door being shown closed.

Fig. 5 is a diagrammatic view of a portion of the structure of Fig. 4 showing the position of the parts when the switch is in the "on" position, with the door yet closed.

Fig. 6 is a diagrammatic view showing parts of Fig. 5 as they appear with the door open.

Fig. 7 is a horizontal sectional view taken substantially upon the plane of line VII of Fig. 4.

Fig. 8 is a further enlarged fragmentary sectional view taken substantially upon the plane of line VIII of Fig. 4, the parts of the switch mechanism being in the "on" position.

Fig. 9 is a similar sectional view showing the parts of Fig. 8 with the switch mechanism in the "off" position and the door open.

Fig. 10 is a detail sectional view taken substantially upon the plane of line X of Fig. 9.

Fig. 11 is a detail perspective view of the connecting link which extends from the switch mechanism to the door.

Fig. 12 is a detail sectional view, similar to a portion of Fig. 4, but showing the manner in which certain portions of the switch mechanism may be disassembled when occasion arises.

Fig. 13 is a horizontal sectional view taken substantially upon the plane of line XIII of Fig. 12.

Fig. 14 is a horizontal sectional view illustrating the manner of connecting a plurality of switch board sections together for completing one larger switch board, and

Fig. 15 is a fragmentary detail sectional view illustrating a modification of the manner of mounting one of the fuse clips.

By way of describing in detail the exemplary structure illustrated in the drawings, the base plate, of the structure is in-

dicated by the reference character L. The switch mechanism, and its connections, are supported at one side of this base plate, while the operating handles project through 5 the base plate to the opposite side thereof.

The bus bars, as 1 and 2, are fixed at the first, or rear, side of the base plate extending vertically thereof.

Branch line wire channels 3 are provided 10 at the rear of the base plate extending approximately throughout the height thereof at the opposite side edges of the base plate. The wire channels are made up of side walls 4 and 5, and a front wall 6, and the two 15 channels collectively define a space between them adapted for containing the switch mechanism.

An intermediate partition 7 is provided substantially midway between the channels 20 and between the sets of bus bars so as to divide said space with one set of bus bars at each side.

The space between the partition wall and either of the channels may be divided vertically 25 by any number of horizontal partitions 8 so as to divide said space into a desired number of superposed pockets, or stalls. In the drawing three such stalls are shown at each side of the partition. Each 30 stall is closed at the rear by a separate guard door G, and each stall is adapted to removably contain one of the switch units. The switch units are each independently formed and independently operable and one 35 such is illustrated at H in Fig. 2, being there shown detached and in position to be inserted in its respective stall.

The switch units each comprise a base board 9, preferably of insulating material, 40 such as slate, and when the unit is inserted in the stall this base board stands substantially parallel with the rear surface of the base plate L but spaced away from said surface so as to constitute a barrier within 45 the stall for the bus bars. The bus bars thus may not be carelessly touched by an operator when the door is open.

At the rear surface of the base board, or barrier, 9, fuse clips 10 and 11 are arranged 50 for supporting fuses 12.

At the forward face of the base board 9 are arranged contact members 13 for the switch blades 14.

The contact members 13 are positioned 55 opposite to the adjacent main line bus bars 1, and there is, of course, one switch blade for each bus bar and one contact 13 for each switch blade. The contacts 13 are electrically connected with the fuse clips 11 60 preferably by means of bolts 15 which extend through the base board to hold the fuse clips and contact members in position.

The fuse clips 10 are carried by plates 16 to which the branch line terminals 17 may 65 be connected, as clearly shown in Fig. 4.

The switch blades 14 are supported by an elongated carrier 18 which is pivoted to rock about its longitudinal axis. Suitable extensions 19 are provided at the opposite ends of the carrier to engage within bearings formed in the supporting plates 20. The blades are spaced apart along the length of the carrier and project laterally therefrom. They are insulated from each other as by means of the insulating strips 75 21. The blades are double ended so in "on" position their opposite ends simultaneously engage the bus bars 1 and the contact members 13 respectively.

The supporting plates 20 are carried by 80 the board, or barrier, 9 by means of bracket plates 22 which are arranged one at each edge of the barrier and at right angles to the plane of the barrier. They are fixed to the barrier by means of bolts, or rivets, 23 85 which extend through the barrier and through portions 24 of the plates which are bent at right angles and which rest against the forward, or inner, surface of the barrier. The supporting plates 20 are riveted, 90 or otherwise secured, to the inner surfaces of the plates 22 and extend forwardly beyond the barrier 9, as clearly indicated.

Of course, it will be understood that any other suitable means may be employed for 95 connecting the supporting plates 20 with the barrier 9. The particular requirement in this connection is that the supporting plates, and all of the parts carried thereby, shall be in turn carried by the barrier so 100 as to be bodily insertible into the stall, and bodily removable from the stall with the barrier. The barrier may be considered as a frame, or carrier, for the switch mechanism, contacts, and fuse clips, by means of 105 which all of said parts may be readily arranged in proper coöperative position with the bus bars.

When moving a switch unit into position within a stall it is simply necessary to rest 110 the lower edge of the barrier upon the horizontal partition 8 forming the bottom wall of the stall and then to move the barrier inwardly until the upper and lower portions of its forward face engage against cross 115 members 25. Attaching screws 26 are then inserted through suitable apertures formed in the cross members to bind the barrier in position.

The cross members 25 are fixed by their 120 outer ends to the walls 4 and by their inner ends to the central partition 7. They are sufficiently wide to project above and below the adjacent horizontal partition 8.

The position of the cross members is such 125 with respect to the rear surface of the base plate L as to properly and positively determine the position of the forward face of the barrier with respect to the bus bars when the barriers are moved home against said 130

cross members. The switch blades, and the contacts 13, are likewise properly positioned by the cross members at the same time.

The walls 4 have openings 27 formed therethrough through which the branch line wires may lead from the wire channels into the respective stalls.

The construction of the switch mechanism, and its manner of control, includes a bell-crank which is pivotally mounted, as at 28, upon the outer supporting plate 20. This bell-crank is preferably made up of two plates, as 29 and 30, spaced apart. At the end of one of the arms, a link 31 is pivotally mounted between the plates and extends into pivotal connection with the switch blade carrier 18, the point of connection with the switch blade carrier being at one side of the pivotal axis, as 32. The bell-crank and the link 31 constitute a toggle by means of which to swing the switch blades to "on" and "off" positions.

An operating rod 33 extends between the plates 29 and 31 and has slot connection with a cross pin 34 at the remaining end of the bell-crank. This operating rod extends forwardly through an opening 35 formed in the face plate L, and is pivotally connected, as at 36, to an operating handle 37. The operating handle is pivotally mounted at a point spaced from the pivot 36, as at 38, so as to serve as a crank to move the rod backwardly and forwardly when the operating handle is swung.

Thus, when the operating handle is moved into a vertical or "on" position, the rod 33 swings the bell-crank and straightens the toggle so as to hold the switch blade "on," as shown in Fig. 4. On the other hand, when the handle is thrown down into the "off" position, the rod 33 is moved backwardly so that the end wall 39 of its slot engages the cross pin 34 and swings the bell-crank to break the toggle and permit the switch blade to snap into "off" position, as shown in Fig. 5.

A coil spring 40 is arranged at the opposite end of the carrier 18 in engagement between the carrier and the adjacent supporting plate 20 so as to exert a constant tendency to move the carrier into the "off" position. The slot in the rod 33 provides for an unobstructed movement of the toggle into "off" position once the toggle is broken.

In order to prevent the guard member, or door G from being opened while the switch is "on," said door is preferably mounted upon hinges 41 adjacent the rear edge of the wall 4, and a link 42 is pivotally connected thereto as by a pin 43 carried by a stud 44 fixed to the door. The stud supports the pin 43 at a point removed from the axis of the hinge.

The link 42 is shaped substantially as shown in Fig. 11, and at its inner end car-

ries a lug 45 which slides backwardly and forwardly along a slot 46 formed in the adjacent plate 20 whenever the door is opened or closed. A transverse head 47 is formed at the outer end of the lug to prevent accidental detachment from the slot.

The plate 30 of the bell-crank above described, is enlarged and is provided with an arcuate slot 48 through which the lug 45 extends, the plate 30 being interposed between the plate 20 and the link 42. One end of the slot 48 terminates in a radial extension slot 49. When the bell-crank is in the "on" position, the lug 45 stands at one end of the arcuate slot 48 and the engagement of the walls of this slot with the lug prevents the lug from moving outwardly along the slot 46, and thus, of course, prevents the door from being opened. So long as the door remains closed, the bell-crank may swing freely during the "on" and "off" movements of the switch mechanism, the lug being at this time accommodated by the arcuate slot. When the bell-crank is in the "off" position, the extension slot 49 will stand in parallelism with the slot 46, and the door may then be opened at will, the lug 45 traveling along the length of the two slots, as clearly shown in Figs. 5 and 6.

After the lug 45 has moved into the slot 49, said lug serves as a positive stop against any return rotation of the plate 30, thus locking the switch mechanism in the "off" position whenever the door is open.

The free edges of the sets of doors at opposite sides of the central partition 7 are supported by an extension strip 50 which preferably projects outwardly from between said doors a sufficient distance to allow a slight opening movement of the door without giving access into the space behind the door. This will take care of any inaccuracies, or looseness offered between the parts connecting the door with the switch mechanism, and will insure an "off" position of the switch mechanism before access is given.

Shoulders 51 are provided at opposite sides of the strip 50 serving as abutments for the doors.

The partitions 7 and 8 are spaced from the rear surface of the face plate L so as to provide for free circulation of air.

It will be seen that by means of this construction the rear surface of the base plate is divided off into a number of well ventilated stalls, each having its independently operable and independently attached, and independently removable switch unit, that each stall is guarded by an independent guard member or door, that each switch unit includes a barrier spaced back of the door providing a safe fuse compartment and a guarded switch compartment, that the door to the fuse compartment may not be opened except when the fuse terminals

are dead, and that the switch may not be moved to "on" position to render the fuses live except when the door is closed.

When it is desired to remove one of the 5 switch units it is simply necessary to throw the switch off, open the door, remove the screws 26 and disconnect the link 42 and the rod 33 from the door and the switch handle, and then lift the switch unit away 10 to be conveniently operated upon to any extent and then as readily returned.

The operating rod 33 preferably moves through a supporting member 52 provided upon the plate 20, and the object of this 15 supporting member is to retain the rod in a substantially horizontal position when the switch unit is detached, as shown in Fig. 2, thus facilitating the proper and easy entrance of the rod into the aperture 35 of the 20 base plate L when moving the switch unit into a stall.

The link 42 may be disconnected from the door by simply lifting out the pin 43 which is preferably provided with a removable 25 cotter pin 53 for this purpose. When the link drops downwardly into the vertical position its head 47 will then register with the slot 46 and may be readily disconnected from the plate 20 if desired.

30 The operating rod 33 may be easily disconnected from the switch handle 37 in the manner suggested in Figs. 12 and 13. This includes first the removal of the pivot pin 38 thus allowing the operating handle to 35 drop so that the pivot pin 36 falls below the lower edge of the bracket plates 54. The pin 36 may then be readily slid out. Until the pin 38 was withdrawn the pin 36 was held against displacement by the opposing 40 bracket plates between which it moved.

When it is desired to provide a very large switch board several of the sections shown in Fig. 1 may be set side by side and connected together as suggested by the sectional 45 view of Fig. 14.

In making the connection the outer wall members 5 of the wire channels are removed and the single cover plate 55 bridges between the adjacent plates 4, thus making 50 an attractive and substantial connection between the sections and at the same time providing a double size channel for the branch line wires which now will lead therealong and in opposite directions to the adjacent 55 stalls at opposite sides of the channel. The brackets 56, to which the walls 5 were connected are now connected together by suitable bolts.

The guard doors G, for all of the sections, 60 may be fitted with spring catches 57 arranged to engage within openings 58 formed in the strip 50.

In Fig. 15 a modification is shown by which the contacts 13, at the rear face of 65 the board or barrier 9, and the plates for

carrying the fuse clips 11, may be made as an integral element instead of depending upon the bolts (as 15, in Fig. 4) for electrical connection. This includes making the contact member and the plates from a single 70 strip of material bent into Z-shape and passed through an opening formed in the barrier, as clearly indicated.

As many changes could be made in this construction without departing from the 75 scope of the invention as defined in the following claims, it is intended that all matter contained in the above description or shown in the accompanying drawings, shall be interpreted as illustrative only and not in a 80 limiting sense.

Having thus described my invention, what I claim as new and desire to secure by Letters Patent is:

1. A switch unit adapted for use as one 85 element of a switch board structure, said switch unit comprising a board, fuse clips supported by the board at one surface thereof, and a switch mechanism supported by the board at the opposite surface thereof 90 and electrically connected through the board with the fuse clips, and the board constituting means whereby to support the switch unit in the switch board structure.

2. A switch unit adapted for use as one 95 element of a switch board structure, said switch unit comprising a board, fuse clips supported by the board at one surface thereof, brackets fixed to the board at the opposite edges thereof, a switch blade carrier 100 pivotally mounted in said brackets at the side of the board opposite to the fuse clips, switch blades supported in said carrier to swing therewith, contacts for the switch blades carried by the board and electrically 105 connected through the board with the fuse clips, and means supported partly by one of said brackets whereby to swing the carrier for moving the switch blades with respect to the contacts.

3. In a device of the class described, the combination with a base plate having a switch handle at one side thereof, switch mechanism at the opposite side thereof, and a connecting rod extending through said 115 base plate connecting said operating handle with said switch mechanism to operate said switch mechanism from said operating handle, of a bracket including a pair of ears between which the operating handle is pivotally mounted, the operating handle including spaced legs between which the end of the connecting rod extends, said legs and rod having mating apertures therethrough, a headless pivot pin extending through said 120 mating apertures to pivotally connect the rod with said legs, said ears having parts disposed to normally stand at all times in position to prevent disengagement of the headless pin from said mating apertures, 130

and means whereby the headless pin may be made to stand in an abnormal position free of said ears to facilitate disengagement of said headless pin if desired.

5 4. A switch unit adapted for use as one element of a switch board structure, said switch unit comprising a board, fuse retaining parts supported by the board at one face thereof, a switch mechanism supported by 10 the board at the opposite face thereof, and the board constituting means whereby to support the switch unit in the switch board structure.

5. A switch unit adapted for use as one 15 element of a switch board structure, said switch unit comprising a board, fuse retaining parts supported by the board at one face thereof, switch blade supporting means extending from the opposite face of the 20 board, a switch blade pivotally mounted upon said switch blade supporting means adapted to swing for performing its appointed function in the switch board structure, and operating means to swing said 25 switch blade.

6. A handle and connections therefor, a pivotal support for the handle comprising a pair of members spaced apart between which a portion of the handle is received, pivot means pivotally connecting said portion of the handle with said pair of members, an element extending between said pair of members, a separately formed pivot member connecting said handle with said element between said pair of members, said 30 pair of members having parts disposed normally to stand at all times in position to prevent disengagement of said separately formed pivot member, and means whereby said separately formed pivot member may 35 be made to stand in an abnormal position free of said pair of members to facilitate disengagement of said handle from said mentioned element.

In testimony whereof I affix my signature 40 in the presence of two witnesses.

HUBERT F. KRANTZ.
